Application July 14, 1941, Serial No. 402,413

9 Claims. (Cl. 315—278)

Our invention relates to fluorescent gas discharge tube lighting systems, and more particularly concerns various features of safety in connection therewith.

An object of our invention, therefore, is to produce a fluorescent gas discharge tube lighting system, including a high leakage reactance autotransformer and hot-cathode fluorescent tubes functioning on cold-cathode operation, having safe operating characteristics upon either failure or removal of a tube from the system.

Another object is to produce a fluorescent gas discharge lighting system employing a high leakage reactance autotransformer, characterized by its safety under all operating conditions, and by freedom from overvoltage upon tube failure, and by deenergization of part or all of the autotransformer upon removal of one or more tubes from the system.

A further important object is to produce a socket for use in the above-described system capable of facilitating the results set forth in the foregoing.

Other objects in part will be obvious and in part pointed out hereinafter.

Our invention accordingly consists in the various elements and features of construction, and in the relation of each of the same to one or more of the others, all as pointed out hereinafter, and the scope of the application of which is set forth in the appended claims.

Referring now to the drawings, wherein are disclosed certain illustrative embodiments of the present preferred forms of our invention, Figure 1 depicts in schematic elevation a form of our invention wherein the energizing supply source is connected across the terminals of the several fluorescent tubes at points within the several branches of the energizing circuit for the primary coils.

Figure 2 discloses in schematic elevation an autotransformer somewhat similar to that illustrated in Figure 1 and having double circuits, together with the related details of the system, but in which the leads of the primary energy source are series-connected across the terminals of the hot-cathode tubes, and in which a cutout relay is provided as an auxiliary load across each secondary coil.

Figure 3 is a schematic view of the electrical part of a third embodiment in which for clarity the transformer core is omitted, inasmuch as the core design is substantially that illustrated in Figures 1 and 2. In this view one leg of the primary energy source is series-connected across

the terminals of each of the two hot-cathode tubes.

Figure 4 is a perspective view with parts broken away for clarity of a socket schematically illustrating certain features of our new invention.

Throughout the drawings, like reference numerals denote like structural parts.

As conducive to a more complete understanding of our invention, it may be stated at this time that more and more, the exploitation of fluorescent gas discharge tube lighting is encroaching on the field heretofore accepted as constituting the province of conventional incandescent bulb lighting. At the present time the acceptance of this new tube lighting is so widespread that it bids fair to replace in large measure such incandescent bulb lighting.

Many reasons readily present themselves as controlling of the rather startling success and acceptance of fluorescent lighting. With no attempt to enumerate all of them, it is interesting to consider but a few of these incidents of practical utility, to permit better comprehension of the reasons dictating the replacement of filamentary lamps by fluorescent gas discharge tubes.

For example, these tubes have only slightly greater first cost, and both the tubes themselves and the auxiliary equipment necessary for use in connection therewith, have a rated life, usually guaranteed, of at least 2½ times the life of filamentary bulbs. Additionally, these tubes have an emission of useful and visible light per unit of power input which is about 2½ times that of the incandescent filamentary bulb. Lamps have been developed in this field and made available on the market, capable of emitting light of various accurately-controlled and pleasing color combinations, hitherto totally unobtainable with

the use of the conventional filamentary bulbs. A wide vista of new modes of utilization is opened due to the considerable length of such tubes and their adaptability to a variety of desired profiles. Because the luminous efficiency of these tubes is greater, the tubes do not give rise to detrimental heating, and the convection and conduction heating which does take place is more readily accommodated by persons in the vicinity of the light sources. Not only do such lamps give rise to more pleasing lighting effects and to more ready accommodation thereof by the users, but as well, these lamps have been found to be admirably suited for floodlighting effects in banks of several tubes. The definite indications are that after certain important constructional and oper-

ational problems are solved, the use of fluorescent tube lighting will become even more universal.

Despite the many practical advantages of these known fluorescent systems, however, there exist certain substantial defects which naturally retard the development of these lighting systems. Thus, for illustrative purposes, attention may be directed to the fact that although these known hot-cathode fluorescent tubes now currently in use have, as described, a greater life span than do the known incandescent bulbs, nevertheless there are serious limitations on that useful life span and the construction of those tubes is such that failure may be predicted with reasonable certainty after a predictable period of service. Accordingly, such hot-cathode tubes can be employed only in systems requiring complicated, costly and fragile auxiliary apparatus, thereby increasing the costs, both initially, for installation, and for maintenance. These hot-cathode tube systems are found to be comparatively slow in starting and to be unstable both in striking and in the maintenance of the arc when cold weather conditions prevail. Lastly, any attempt to operate the tubes on currents lower than the values for which the tubes are rated in order to produce light emission of lower intensity, is met with both unstable operation and marked decrease in the life of the filamentary electrodes which form an essential part of the known hot-cathode tubes.

In our co-pending applications, Serial Nos. 402,410, 402,411 and 402,412, filed July 14, 1941, we have illustrated and described new forms of fluorescent gas discharge tube lighting systems employing high-leakage reactance autotransformers therein and capable of using hot-cathode fluorescent tubes on cold-cathode operation.

As disclosed in our said co-pending applications we have discovered that fluorescent lighting systems functioning on cold-cathode operation give rise to many practical and important advantages as contrasted with the conventional hot-cathode operation. We have stated in our co-pending applications that we can employ either fluorescent tubes made up especially for cold-cathode operation, in which case the tubes could be obtainable on special order, or the hot-cathode tubes now readily available on the market, these hot-cathode tubes being adapted for cold-cathode operation by short-circuiting the filamentary electrodes thereof.

Among the aforementioned advantages flowing from the cold-cathode operation may be listed the provision of the required high starting voltages with automatic adjustment to the lower operating voltages once the arc across the tube is struck, all in the absence of complicated auxiliary equipment. The separate ballast, starting switch, and compensator heretofore considered necessary are no longer required when recourse is had to our new lighting system. As is fully set forth in our co-pending applications, tubes so operated are quick starting, have long tube life, possess stable starting and operating characteristics during prevailing cold weather, have longer duration of light emission during each half-cycle of energizing current, and will function on dimmer operation, that is, on light emissions lower than that for which the tube is rated. Our new system has comparatively low current demand, is simple, reliable, compact and extremely sturdy.

It is the purpose of this application to set forth various important safety features which

we have designed for use in connection with systems of the types set forth in our said co-pending applications. We accomplish this objective by connecting the leads from the primary source of energy, either before or after those leads are branched to the one or more primary coils, in series across the dual terminals of either one or both hot-cathode fluorescent gas discharge tubes which may be employed in our new electrical systems. This connection of the energy source across the tube may be accomplished illustratively by the use of a specially designed socket, employing broadly the constructional features illustrated in Figure 4 herein.

Referring now to the constructional embodiment disclosed, solely by the way of illustration and not by way of limitation, in Figure 1, we may preface our discussion thereof by calling attention to the fact that the autotransformer according to our invention may have either a single or a double secondary circuit, and the core may be constructed to provide either a single or double magnetic circuit. Furthermore, assuming that the high-leakage reactance transformer is of the double magnetic circuit type, employing two primary coils one in each magnetic circuit, then these primary coils may be connected either in parallel or in series across the source of energy supply.

In the embodiment illustrated in Figure 1 and now under discussion, we disclose, for purposes of illustration, an autotransformer of the high-leakage reactance type having two secondary circuits and constructed to provide two groups of parallel magnetic paths, and in which we connect the two primary coils in parallel across the source of primary energy.

With the foregoing in mind, we observe that the transformer core consists of a central, longitudinally extending leg 10, of magnetic material, and outer legs 11, 12 of like material disposed on opposite sides thereof and extending in spaced relation therewith. Mid core portions M1 and M2 and end pieces 13, 13 and 14, 14 serve to interconnect magnetically the outer and inner legs near their centers and at their ends, respectively. In this manner the transformer core is divided into two groups of parallel magnetic paths. In the first group one path is traced up core portion M1, to the right in Figure 1 along leg 11, through first end piece 14, to the left across leg 10, and back to M1, and another path is traced down core portion M2, to the right across leg 12, through the lower end piece 14 and to the left across leg 10 back to M2. In the second group of magnetic paths a path may be traced down core portion M2, to the left in Figure 1 along leg 12, up second end piece 13, to the right across leg 10, and back to M2, while a second path may be traced up through M1, to the left along leg 11, down the upper part of core portion 13 and back across leg 10 to M1. It is apparent, therefore, that these two groups of parallel magnetic paths have a leg in common consisting of the core portions M1, M2 and that portion of central leg 10 embraced therebetween.

In each group of parallel magnetic paths the mid core portions M1, M2, outer legs 11, 12 and end pieces 13, 13 and 14, 14, respectively, define a pair of spaces, one on each side of central leg 10. The pair of spaces within each group of magnetic paths is designed to receive the primary and secondary coils for that particular group of magnetic paths. The coils are disposed about central leg 10, with the primary coils disposed

adjacent the common magnetic leg, for reasons which will be more fully developed hereinafter.

In each pair of spaces there extends from the legs 11, 12, respectively, between said primary and secondary coils, towards but short of the central leg 10, intermediate shunts of high reluctance calibrated in accordance with the load for which the transformer is designed. The mid-core portions, end pieces, and intermediate shunts are all formed of magnetic metal.

The construction of the transformer core, except for some minor details which will be pointed out from time to time in the following text, is substantially the same in the three illustrative embodiments described in this specification. Accordingly, no attempt will be made to describe in detail the construction of the transformer core shown in Figure 2, while the transformer core has been entirely omitted in Figure 3.

Thus, in the embodiment according to Figure 1, a primary coil P1 and a secondary coil S1 are disposed in the pair of spaces provided in the first group of parallel magnetic paths, to the right in Figure 1 of the common magnetic leg. Similarly, a primary coil P2 and a secondary coil S2 are provided in the second group of parallel magnetic paths to the left in Figure 1 of the common magnetic leg. In each instance it will be seen that the primary coils are adjacent the common magnetic leg while the secondary coils are adjacent the end legs 14, 10, 14 and 13, 10, 13, respectively. Intermediate shunts Sh1 and Sh2 extend from legs 11 and 12 respectively between primary and secondary coils P1 and S1 towards but short of central leg 10. The shunts Sh1, Sh2 thus provide between their one ends and the leg 10, air-gaps G1 and G2 of high reluctance calibrated in accordance with the particular load for which the transformer is designed.

In like manner, intermediate shunts Sh3 and Sh4 extend between the secondary coils S1 and S2 from outer legs 11 and 12, respectively, towards but short of central leg 10. They provide therebetween air-gaps G3 and G4 of high reluctance calibrated in accordance with the particular load for which the transformer is designed.

A source of primary energy 15 is adapted to be connected across the primary coils P1, P2. This connection may be either series or parallel. Series connection provides for a potential drop across each primary coil of but half the total voltage output of the source of energy 15. Thus, for the same potential drop across each coil for either parallel or series connection thereof, the series connection possesses the advantage that higher service voltages may be employed, with consequent saving in transmission losses. The disadvantage is present, however, that upon failure of either primary coil the associated primary coil likewise becomes deenergized. Where parallel connection of the primary coil is utilized, each coil takes the full potential of the energy source independently of the other coil. In the present embodiment the energy source 15, as has been stated hereinbefore is parallel-connected across primary coils P1, P2.

In this embodiment, however, before discussing the energizing circuit it will be interesting first to develop the secondary circuits. Thus, secondary coil S1 is provided with right and left-hand terminals 16, 17; primary coil P1 with right and left-hand terminals 18, 19; primary coil P2 with right and left-hand terminals 20, 21; and secondary coil S2 with right and left-hand terminals 22, 23. In circuit with secondary coil 75

S1 is a fluorescent gas discharge tube T1, while in circuit with secondary coil S2 is a fluorescent gas discharge tube T2. These tubes T1, T2 are of the conventional hot-cathode type which now can readily be obtained on the open market. Conventionally they consist of an elongated glass tube containing a filling of suitable inert gas and a small quantity of mercury and forming a space discharge path and being interiorly coated with a suitable fluorescent salt, the secondary radiation of which is visible and of the desired color. A base is provided at each end of the tube, on which base is mounted a filamentary electrode. Two terminals, one connected to each end of said filamentary electrode, project exteriorly from the tube through the corresponding base. These electrodes are intended to be connected across a source of electrical energy. The filamentary electrode serves to prepare the tube for the maintenance of an arc discharge thereacross. Once the arc is struck the filament is taken out of operation and the arc is maintained directly between the spaced electrodes.

Each secondary coil and its associated tube is 25 series-connected across the network consisting of the parallel-connected primary coils P1, P2. Thus for example a circuit may be traced from secondary coil S1, terminal 16, lead 24, socket 25, across tube T1, to socket 26. From there one 30 branch circuit may be traced from leads 27 and 28 to terminal 19 of primary coil P1, thence to the right through said primary coil to terminal 18, and thence through lead 29 to terminal 17 and back through secondary coil S1. Another branch 35 circuit may be traced from socket 26 through lead 30 to terminal 21 of primary coil P2, thence to the right in Figure 1 through primary coil P2, across terminal 20, through leads 31 and 32 to socket 33, and thence through lead 29 and terminal 17 back to secondary coil S1.

At the same time circuits may be traced through the other secondary coil S2 and tube T2 as follows: The first circuit may be traced from terminal 22 of secondary coil S2 across lead 30 to terminal 21 of primary coil P2, thence to the right in Figure 1 through primary coil P2, down through terminal 20 and leads 31, 32 to socket 33, thence across tube T2 to socket 34 and back through lead 35, terminal 23 and to the right 50 in Figure 1 across secondary coil S2 to the point of beginning. The other branch of this secondary coil may be traced from terminal 22, across lead 30, socket 26, leads 27 and 28 to terminal 19, to the right in Figure 1 across primary coil P1 down terminal 18, across lead 29, to socket 33, across tube T2 to socket 34, and back up through lead 35 and terminal 23 to secondary coil S2.

The foregoing circuits have been traced for an assumed half-cycle of current flow. During the 60 next subsequent half-cycle of current flow, the direction of current flow will be just the opposite to that described.

An important feature of our invention is the design of the sockets for receiving the dual terminals of one end of each tube. The sockets 26, and 33 in the embodiment undergoing description are constructed in such manner that the primary charging circuit for one or both of the primary coils P1, P2 is completed upon insertion of the 65 corresponding tube into its socket, and is broken upon removal of the tube therefrom. In this manner it is ensured that the primary coil is de-energized upon the removal of the corresponding tube.

With the foregoing in mind, we are now in an

advantageous position to discuss the charging circuits for the two primary coils P_1 , P_2 . Let us assume a half-cycle in which current flows to the right from energy source 15, up through lead

28. One branch of the primary supply network extends through terminal 19, to the right in Figure 1 through primary coil P_1 , back through terminal 18 and lead 29 to socket 33, across that socket to lead 32, and back through lead 31 to the left-hand side of the energy source 15. It is especially important to note that this parallel charging circuit includes therein the pair of terminals of tube T_2 which engage in socket 33. Upon removal of tube T_2 , accordingly, this branch of the primary network is deenergized, and primary coil P_1 likewise is deenergized.

The other primary charging circuit can be traced from the right-hand side of energy source 15 through lead 27, across socket 28 to the terminals of tube T_1 , and through lead 30 to terminal 21 of primary coil P_2 , then down through terminal 20 and lead 31 back to the left side of energy source 15. Here again the two terminals of tube T_1 are received in a socket and are included in the circuit energizing primary coil P_2 . In the alternate half-cycles of current flow the direction of the primary charging current is just the reverse of that described.

Let us assume that tubes T_1 and T_2 are both inserted in sockets 25, 26 and 33, 34, respectively, and let us further assume that the switch (not shown) is closed across energy source 15. Both primary coils P_1 and P_2 are then energized through the circuits previously described. Now let us assume that it is desirable to remove say tube T_1 . Upon removal of this tube the charging circuit through primary coil P_2 is broken at socket 28, due to the fact that the pair of terminals at the left end of the tube T_1 are normally included by socket 28 in this charging circuit. Primary coil P_2 immediately becomes deenergized. Primary coil P_1 , however, remains energized. Since however, the secondary circuit through tube T_1 is broken by the removal of this tube, there can be no current flow through the load circuit of secondary coil S_1 . Similarly, since the return circuit for the tube T_2 and secondary coil S_2 and including primary coil P_1 is through the socket 26, and further, since the circuit through this socket is broken upon the removal of the tube T_2 , it will be seen that the tube T_2 likewise is deenergized, upon removal of the tube T_1 .

At this time we will develop for the embodiment undergoing discussion the manner in which the flux courses the several magnetic paths in the transformer core. Since the coursing of flux is substantially the same in the cases of the embodiments of Figures 2 and 3, and since the principle involved is the same, and further, since the core is not illustrated in Figure 3, discussion of the flux circuits in these two embodiments will be omitted.

While it is possible to connect the primary coils P_1 , P_2 in either aiding relationship on the one hand, or opposed or bucking relationship on the other hand, we are elect for purposes of illustration to show them as connected in bucking or opposed relationship. This gives rise to a slight increase of efficiency, in aiding what may be termed a shift of flux upon increase in load across one secondary circuit prior to similar increase of load in the other secondary circuit. In such a case the flux increases in the magnetic path containing the unloaded secondary circuit. Where the coils

are connected in aiding relationship, the mid-core portions M_1 , M_2 may be materially reduced in size, or in a number of instances, entirely eliminated.

5 Assume a momentary half-cycle of current flow such that the primary flux generated by the passage of the current through the primary coils is in the direction shown by the arrows in Figure 1. Then discussing the first group of magnetic 10 paths for purposes of illustration, the flux coming from coil P_1 passes to the left in Figure 1 to the common magnetic leg. There it bucks the flux from coil P_2 which tends to flow in the opposite direction across this leg. Accordingly, the 15 primary flux from coil P_1 splits into two streams which course in opposite directions along this leg. The outer legs 11 and 12 being substantially symmetrical with reference to leg 10, as well as the shunts Sh_1 , Sh_2 , these two streams of flux are substantially equal. One stream courses up through mid core portion M_1 and to the right in Figure 1 along leg 11. Choosing the paths of least reluctance, only a very little of the flux courses at this time down through shunt Sh_1 . 20 By far the greater part of the flux courses to the right along leg 11, and down first end piece 14, to the right-hand end of central leg 10. The other stream of flux courses down through mid core portion M_2 and to the right in Figure 1 along outer leg 12. Likewise choosing the paths of least reluctance, only a very small part of this flux courses along shunt Sh_2 . By far the larger part thereof courses up through second end piece 14, to the right-hand end of leg 10. The two 25 streams of flux re-unite at central leg 10 and the combined stream courses to the left along leg 10 to primary coil P_1 . In so doing this combined stream interlinks secondary coil S_1 , and generates therein a high voltage. Inasmuch as the 30 arc load across the secondary coil has not yet been energized, coil S_1 interposes but little impedance at this time.

At the same time, a similar flux circuit may be traced for the flux from the primary coil P_2 . 45 Flowing to the right in Figure 1 along central leg 10 from primary coil P_2 , the primary flux bucks the primary flux from coil P_1 in the common magnetic leg and splits into two streams. Because of the symmetry of the two legs 11, 12 50 as well as the shunts Sh_3 , Sh_4 , these two streams of flux are substantially equal. One stream courses up core portion M_1 and to the left in Figure 1 along leg 11. Seeking the paths of least reluctance, only a very small part of this flux 55 courses down along shunt Sh_3 . By far the greater part of the flux courses to the left across leg 11, down first end piece 13, to the left-hand end of central leg 10. The two streams of flux re-uniting at leg 10, the combined stream courses to the right in Figure 1 along leg 10, back to primary coil P_2 . During this movement the combined stream of flux interlinks secondary coil S_2 and induces a high secondary voltage therein. 60 Inasmuch as the arc load across this secondary coil is not energized, the secondary coil S_2 interposes but little impedance at this time.

During the next current half-cycle, the direction of coursing of the flux is just the reverse of 65 that described. Inasmuch as the direction of coursing of the flux is substantially the same in the two parallel magnetic circuits, it is sufficient for purposes of illustration to describe the direction of reverse coursing for but a single secondary circuit. This will be done in connection with the

first group of parallel magnetic circuits. The flux now courses in a direction contra to that indicated by the arrows. The combined stream of flux now courses to the right in Figure 1 from primary coil P_1 along leg 10 , interlinking secondary coil S_1 and inducing a high secondary voltage therein. At the right-hand end of leg 10 the flux splits into two equal streams. One stream courses up through first end piece 14 , and to the left in Figure 1 along outer leg 11 . Seeking the paths of least reluctance, only a very small part of this flux courses down through shunt Sh_1 . By far the greater part of the flux continues to the left in Figure 1 along leg 11 , and courses down mid core portion M_1 to central leg 10 . Simultaneously the other stream of flux courses down through second end piece 14 and to the left along leg 12 . Likewise seeking the paths of least reluctance, only a very small part of this flux courses up through shunt Sh_2 . By far the greater part of this flux continues to the left along leg 12 and courses up core portion M_2 , to central leg 10 . The two streams re-unite at leg 10 and they course back to primary coil P_1 . During the next subsequent half-cycle of charging current the path of the flux from primary coil P_1 is of course just the reverse of that indicated by the arrows in Figure 1.

While the tubes T_1 and T_2 are supposedly of like electrical characteristics, as well as the sockets 25 , 26 , 33 and 34 and secondary coils S_1 and S_2 , nevertheless almost invariably there are some slight differences in the impedances offered thereby, so that one of the secondary circuits will be found to have a somewhat greater impedance than does the other secondary circuit. The arc is found to strike first across the tube in the circuit of lower impedance. Let us assume that it is the circuit including tube T_1 and coil S_1 which has the lower impedance. Accordingly, after the passage of but a comparatively few current cycles, the tube T_1 , operating with its terminals short-circuited by sockets 25 , 26 so that it functions on cold-cathode operation, is brought into a condition of such excitation that the arc strikes thereacross.

Immediately a comparatively large current begins to flow across the tube and its associated secondary coil S_1 . Because this tube and the corresponding secondary coil are series-connected across the primary network consisting of coils P_1 and P_2 , this same increased current flows across that network and splits inversely in the ratio of the impedances of those two coils, each of which is disposed in a separate branch of that primary network. Since the primary coil P_1 increases in impedance upon striking of the load across coil S_1 , magnetically in circuit therewith, due to its increase in inductive reactance, the greater part of the current is impressed across the branch of the primary network which includes primary coil P_2 . The flux generated depending upon the ampere turns in the primary coils and the number of turns being a constant, the primary flux generated by coil P_2 and coursing through the second magnetic path increases upon this increase in charging current. The increased flux results in the induction of a still higher voltage in secondary coil S_2 , which is impressed across tube T_2 . This increased voltage results in almost instantaneous striking of the arc across that tube.

As soon as the arc is struck across tube T_2 and current begins to flow through the corresponding secondary coil, this current flow gives

rise to a back magnetomotive force in that coil. A secondary flux is developed therein which bucks or opposes primary flux tending to interlink secondary coil S_2 .

To develop this phenomenon, let us refer again to the first group of magnetic paths, including coils P_1 , S_1 and let us trace the coursing of the primary flux. Assuming current flow such that the flux courses in the direction of the arrows, then the body of primary flux courses along leg 10 to the left in Figure 1 from the primary coil P_1 . Splitting into two equal streams at the common magnetic leg and for the reasons already described, one stream courses up core portion M_1 and to the right in Figure 1 along leg 11 . The flux seeking the paths of least reluctance, only a very small part continues on down through first end piece 14 to the right-hand end of central leg 10 and then back to the left in Figure 1 along that leg to primary coil P_1 , interlinking coil S_1 . By far the greater part of this stream of flux courses down through shunt Sh_1 and across air-gap G_1 to leg 10 . This high reluctance shunt path is now of lower reluctance than is the path interlinking coil S_1 since this secondary now develops a higher counter magnetomotive force due to the energization of the load thereacross. Simultaneously the second stream of magnetic flux continues down through core portion M_2 and to the right in Figure 1 and along leg 12 . Only a small part of the flux continues up through second end piece 14 to leg 10 interlinking coil S_1 and coursing back to the left in Figure 1 along leg 10 to primary coil P_1 . By far the greater part of this flux courses up through shunt Sh_2 and across air-gap G_2 to central leg 10 . The two streams of flux there re-uniting, they course to the left in Figure 1 along leg 10 back to primary coil P_1 , completely shunting or by-passing secondary coil S_1 . An important feature of the design of this transformer is that the intermediate shunts Sh_1 and Sh_2 and their associated air-gaps G_1 , G_2 have just sufficient reluctance to ensure that enough, but no more than enough, flux interlinks secondary coil S_1 after the load across the latter has been energized, to induce therein a voltage sufficient to support the arc load disposed thereacross.

In the next half-cycle of current flow the direction of coursing is just the reverse of that described. The flux courses to the right in Figure 1 along central leg 10 from the primary coil P_1 . Only sufficient flux interlinks coil S_1 to induce therein the voltage necessary to maintain the arc across tube T_1 . At the right-hand end of leg 10 the small part of flux which interlinks coil S_1 splits into two streams, one of which flows up along first end piece 14 , through leg 11 to the left in Figure 1, down core portion M_1 to leg 10 and back to primary coil P_1 , while the other stream courses down second end piece 14 , along leg 12 to the left in Figure 1, through core portion M_2 and leg 10 back to primary coil P_1 . By far the greater part of the flux splits into two streams. One stream courses up across air-gap G_1 , through shunt Sh_1 , to the left along leg 11 , through core portion M_1 to leg 10 . The other stream courses down across air-gap G_2 , through shunt Sh_2 , to the left along leg 12 , up through core portion M_2 , to leg 10 . The two streams of flux there re-uniting, they flow back to right in leg 10 to primary coil P_1 .

Since the direction of the coursing of the flux, in the group of parallel magnetic paths embracing the coils P_1 and S_1 during such times as the

load across secondary coil S2 is energized, is just the same as has been described immediately hereinbefore in connection with the other group parallel magnetic paths, it is unnecessary to trace the coursing of the flux for this second parallel magnetic path, and such description will be omitted, for simplicity.

While in the embodiment just described, removal of one of the tubes from its sockets will result in deenergization of the primary coil in that branch of the primary network in which the tube is connected, and will result also in the deenergization of both tubes, we find that the other primary coil remains energized, and is supplying a reduced quantity of flux to both secondary coils. Inasmuch as the secondary circuit including the tube which has not yet been removed is broken by the removal of the one tube, however, the remaining tube is deenergized. The coursing of the flux from that primary coil which remains energized, however, gives rise to an induced voltage in the secondary coil which was in circuit with the tube which was removed, so that the open sockets cooperating with that tube will be at the comparatively high potential induced in the corresponding secondary coil and thus represent a source of potential hazard, should accidental contact be made thereacross.

It is the purpose of the embodiment according to our Figure 2, which will now be described, to eliminate even this slight and rather remote danger. Therein the leads 28 and 31 from the source of primary energy 15 are connected across the socket of tubes T1 and T2 at points before the leads are branched off to the respective primary coils. The removal of either tube, therefore, is followed by complete deenergization of the entire system. This can be demonstrated by tracing the primary circuits.

Assuming a momentary current flow such that the current flows to the right in Figure 2 from the supply source 15, then a circuit can be traced through lead 28 to socket 26, across the terminals at the corresponding end of the hot-cathode tube T1, thence through lead 28 to junction 36. From junction 36 one branch extends through lead 31 and terminal 21, to the right in Figure 2 through primary coil P2 to terminal 20, and thence through lead 31, socket 33, across the paired terminals of the corresponding end of the hot-cathode tube T2, and thence through lead 31 back to the left-hand side of energy source 15. The other parallel branch of this primary network can be traced from junction 36 to terminal 19, thence to the right in Figure 1 through primary coil P1, down across terminal 18 and through lead 38 to junction 39, thence through lead 31 to socket 33, across the paired terminals of the corresponding end of the hot-cathode tube T2, and back through lead 31 to the left-hand side of energy source 15. During the next half-cycle of the current flow, of course, the direction of the coursing of the current is exactly the opposite of that just traced. The primary coils P1, P2 are connected in opposed relationship and the construction of the core follows the same teachings as have been described hereinbefore in connection with Figure 1. Thus the coursing of the flux through the several magnetic paths and upon the occurrence of the various phenomena there described is just the same as has already been narrated. Repetition is unnecessary at this point.

The secondary coil electrical circuits may be traced as follows: One such circuit extends from

the right-hand terminal 16 of secondary coil S1, through lead 24 to socket 25, across tube T1 to socket 26, through lead 28 to junction 36. The other leg of this circuit can be traced along left-hand terminal 17 of secondary coil S1 and lead 38 to junction 40. From junction 36 one branch circuit may be traced through lead 31, left-hand terminal 21 of primary coil P2, through primary coil P2 to the right in Figure 2, to terminal 20, thence to junction 39 and back across lead 38 past junction 40 to the left-hand terminal 17 of secondary coil S1. A similar parallel circuit can be traced from junction 36, through left-hand terminal 19, to the right in Figure 2 across primary coil P1, thence down right-hand terminal 18 to junction 40 and back to secondary coil S1.

A similar secondary circuit may be traced from right-hand lead 22 of secondary coil S2, and across lead 37 to junction 41. The other leg of this secondary circuit may be traced from the left-hand terminal 23 of secondary coil S2, through lead 35 to socket 34, across tube T2 to socket 33 and up lead 31 to junction 39. From junction 41 one branch circuit may be traced through left-hand terminal 21, through primary coil P2 to the right in Figure 2, and along right-hand terminal 20, back to junction 39. A similar branch may be traced from junction 41 through lead 37, junction 36, left-hand terminal 19, through primary coil P1 to the right in Figure 2, right-hand terminal 18, junction 40 and back through lead 38 to junction 39. Of course during the next subsequent half-cycle of the charging current, the direction of current flow is just the reverse of that described.

The important part about this construction is that upon removal of either tube from its sockets, open-circuit conditions maintain in one of the primary leads from the energy source 15, so that the entire system becomes deenergized. It is further to be noted that because the primary coils are deenergized, then upon removal of a tube no high potential secondary voltage is impressed across the corresponding tube sockets. Thus all hazards otherwise attendant upon removal of a tube from the system are substantially eliminated.

A further refinement according to our invention is illustrated in this figure, and relates to the provision of a cutout relay across each secondary coil, these relays having impedance characteristics such that they do not come into operation during the normal functioning of the tube lighting system, and are energized only upon failure of the tube in the circuit of the corresponding secondary coil.

We find that when one of the tubes fails, thereby discontinuing the development of appreciable secondary current by the corresponding secondary coil, the quantity of primary flux coursing through this secondary coil induces therein a high open-circuit voltage. While the secondary coil can withstand this high voltage for the comparatively short space of time required to strike initially the arc across the corresponding tube, this elevated voltage represents a source of danger where it endures for any appreciable period of time.

Accordingly, we provide a cutout relay across each secondary coil, which is insensitive to the normal operating voltage of the coils, and which has such inertia characteristics that it does not attract its associated armature for some little time after the high voltage conditions are first

initiated. Thus these relays do not come into operation during the starting period. It is quite possible to design the relay in such manner that there is no danger of their cutting in, even during comparative sluggish operation under cold weather conditions.

Thus, armature coil 42 is inserted by leads 43, 44 and 45, 46 across secondary coil S1. In the lead 47 constituting a continuation of lead 43 resistance 48 is inserted. Armature 49 coacts with coil 42 and is adapted to contact against terminal 50 of lead 47. This relay is so sluggish that it does not function during the starting of the tube. Its impedance characteristics are such that it is insensitive to the normal operating voltage of coil S1. Upon failure of tube T1, however, and prior to removal of this tube from the system, as for example when a tube fails during unattended night illumination and the high voltage current then induced in secondary coil S1 endures for a considerable length of time, coil 42 is energized sufficiently to attract armature 49 against terminal 50 and hold it there, thus completing a circuit from coil S1 through the resistor 48. This resistor is designed to have a reactance corresponding to that of the tube load.

Similarly, a relay coil 51 is connected by leads 52, 53 and 54, 55 across secondary coil S2. A resistor 56 is inserted in a lead 57 forming a continuation of lead 5. Armature 58 coacts with coil 51 and is associated with a terminal 59 of lead 57. The operation is exactly the same as has been described immediately in the foregoing in connection with relay 42 and need not be repeated at this point.

All danger of damage to the transformer upon failure of a tube is eliminated. The system can continue in operation on the other tube without detrimental result from the electrical standpoint.

The system according to Figure 3, as already pointed out, employs generally the same high leakage reactance transformer core as has been described hereinbefore with respect to Figures 1 and 2. Repetition of this description therefore becomes unnecessary at this point. Accordingly, both illustration and description of the transformer core has been entirely omitted with reference to the embodiment according to Figure 3, it being understood, however, that the design of the core in large measure follows the teachings set forth hereinbefore with reference to Figures 1 and 2.

The electrical circuits of the system according to Figure 3 are in large part patterned after those depicted in Figure 2. Hot-cathode tubes are similarly employed on cold-cathode operation, and advantage taken of details of construction of those hot-cathode tubes to give rise to certain features of safety forming the subject matter of this invention. The important demarcation exists between the construction according to the present embodiment, however, and that of Figure 2 in that in the instant case, a single lead from the primary source of electrical energy is series-connected, before it reaches the parallel-connected network for energizing the primary coils, across the paired terminals of not one, but both hot-cathode tubes employed. The other lead from the primary source may be connected directly to the secondary coil network.

It may be briefly stated that this embodiment employs a transformer having two groups of magnetic paths, with two sets of windings, one set in each group of magnetic paths, and each set consisting of a primary and a secondary

coil. The primary coils are connected in parallel-opposed relation across an energy source; and each secondary coil, together with a series-connected tube load, is inserted in series across the network consisting of the parallel-connected primary coils.

Thus primary coils P1 and P2 are connected in parallel-opposed relation across a source of alternating-current electrical supply 15. Secondary coils S1 and S2 each have a hot-cathode fluorescent gas discharge tube T1 and T2, respectively, series-connected thereacross for functioning on cold-cathode operation. Sockets adapted to short-circuit the paired terminals of the hot-cathode tubes serve to condition these tubes for the desired cold-cathode operation. These tubes T1 and T2 are of the same hot-cathode fluorescent gas discharge type previously described. They consist of glass tubular walls, lined with fluorescent salts, and contain a filling of suitable inert gas, and a drop of mercury. Paired electrodes extend exteriorly from filamentary electrodes at each end of the tube.

Thus, for a given half-cycle of current flow, a circuit may be traced from the energy source 15, to the left in Figure 3, up lead 60 to junction 61. One branch of the parallel network can then be traced up lead 62, to the left in Figure 3 across primary coil P2, down lead 63 to junction 64. Thence a return circuit may be traced through lead 65, across socket 25 of tube T1, through lead 66 to socket 33 of tube T2, and through lead 67 to the right-hand side of energy source. Similarly, another branch charging circuit simultaneously exists, traced from junction 61, across lead 68 to the right in Figure 3, up lead 69, across primary coil P1 to the left in Figure 3, and down through lead 70 to junction 64. During the next half-cycle of current flow the coursing of the circuit is just the reverse of that described.

Upon removal of either tube it will be noted that the primary energizing circuit is broken, thus deenergizing both primary coils. Thus upon removal of tube T1 from its sockets, the primary circuit is broken at socket 25, while upon removal of tube T2 from its sockets, this same primary circuit is broken at socket 33. Both primary coils become deenergized, and the secondary system is completely dead.

Secondary circuits energized by potentials induced in each secondary coil, each include a corresponding space discharge tube T1 and T2, and are series-connected across the primary network. One such secondary tube circuit may be traced, for an assumed half-cycle, from the end of secondary coil S1 at the right in Figure 3, through lead 71 to socket 26, across tube T1, socket 25, and lead 65 to junction 64. Another leg of this circuit may be traced from the left-hand end of secondary coil S1, down through lead 72 to junction 73. From junction 64 one branch may be traced through lead 63, to the right in Figure 3 across primary coil P2, down through lead 62, junction 61 and lead 68 to junction 73. The other branch may be traced simultaneously from junction 64, lead 70, to the right in Figure 3 through primary coil P1, and down through lead 69 to junction 73.

Similarly, a corresponding set of circuits may be traced for simultaneous current flow through secondary coil S2 and tube T2. From the end of coil S2 at the right in Figure 3, current flows through lead 74, socket 34, tube T2, socket 33, lead 66, across socket 25 and lead 65 to junction 64. The other left of this circuit includes the

terminal of coil S2 at the left in Figure 3, and lead 75 to junction 61. One branch circuit may be traced from junction 64, lead 63, to the right in Figure 3 through primary coil P2, and lead 62 back to junction 61. Simultaneously a second branch circuit is established from junction 64, lead 70, to the right in Figure 3 through primary coil P1, lead 68, junction 73 and lead 68, back to junction 61.

During the next half-cycle of current flow, of course, the direction in which the current traverses these circuits is exactly the opposite of those traced. The polarity is reversed.

While as suggested, the sockets which can be utilized in connection with our invention can assume any of a number of different structural embodiments, we illustratively disclose a satisfactory example of such socket in Figure 4. The essential requirement of such socket is that the sleeves for receiving the terminals of the corresponding tube be provided with a short-circuiting jumper extending therebetween, and through which jumper a circuit is completed only upon insertion of the tube terminals in those sockets.

Referring to Figure 4, the socket pictured therein solely by way of illustration consists of an outer shell 76 which conveniently may be of metal of other suitable material. Disposed within the cylindrical shell 76 are tubular sleeves 77, 78, paired to receive the extending terminals which are disposed at one end of a fluorescent gas discharge tube, and formed of suitable insulating material, such as rubber, molded plastic, or the like. In any desired manner these sleeves are spaced from the shell 76, as by the introduction of a suitable cement filler or the like. A metal jumper 79 extends between the sleeves 77, 78, and presents a metallic bearing surface on the interior of those sleeves. Leads 80 and 81 extend from the interior of the respective tubular sleeves to the exterior of the shell 76, preferably rearwardly or laterally, and are intended to be connected in the electrical circuit with which the socket is associated, thus completing a circuit across said metal jumper when a tube is inserted in the socket. Should the particular socket 76 be intended for use at that end of an associated tube which has only one current lead, then the leads 80 and 81 are preferably connected together for purposes of safety, since both leads would be at the same potential, and the joined leads are then connected in an electrical circuit.

The several features of safety forming the subject matter of this invention permit us to operate our high voltage, cold-cathode fluorescent gas discharge systems without danger resulting from either failure or removal of one or more tubes forming part of the lighting system. Upon removal of a tube according to the embodiment of Figure 1, one of the primary coils is deenergized, and the remaining tube is likewise deenergized. In the embodiment according to Figures 2 and 3 removal of those tubes is attended by deenergization of both primary coils. Further, as we illustrate in connection with Figure 2, failure of one of those tubes, which nevertheless is physically retained in the system, is attended by the automatic establishment of a shunt circuit through a relay-controlled branch, with attendant assurance that no detrimental high voltages will maintain in the circuit.

We claim:

1. A fluorescent gas discharge tube lighting system comprising, a transformer having a pri-

mary winding and secondary winding; a fluorescent tube; a pair of sockets into which said tube is positioned connected to said secondary winding; and connections between the primary winding and a source of alternating current electrical energy by way of at least one of said pair of tube sockets with its terminals connected in series therewith, said one socket being so constructed that insertion of the tube short-circuits the socket terminals and removal of the tube therefrom interrupts the circuit source to the primary winding.

2. A fluorescent gas discharge tube lighting system comprising, a transformer having two groups of windings each including a primary winding and a secondary winding with the primary windings connected together, two fluorescent lighting tubes individually corresponding to the groups of windings, a pair of sockets associated with each tube, and electrical connections between the transformer and sockets, with the terminals of at least one of said sockets in series with one primary winding so that insertion of its associated tube completes the circuit through said primary winding and removal of the tube deenergizes the primary windings of both groups by interrupting the connections thereto.

3. A fluorescent gas discharge tube lighting system comprising, an autotransformer having a primary winding and secondary winding, the primary winding being connected across a source of alternating current electrical energy; and two fluorescent lighting tubes mounted in two pairs of sockets corresponding thereto, the pairs being individually connected in secondary circuits with the autotransformer, and at least one socket of each pair being serially connected between the transformer and source of supply energy so that insertion of the related tube short-circuits the terminals of the socket and removal of the tube interrupts the circuit source to the primary winding.

4. A fluorescent gas discharge tube lighting system comprising, a transformer having a primary winding and two secondary windings, the primary winding being connected across a source of alternating current electrical energy; and two fluorescent lighting tubes with their tube terminals mounted in two series of sockets individually corresponding thereto, the pairs being individually connected in secondary circuits with the secondary windings, and at least one socket of each pair being serially connected between the transformer and source and so constructed as to complete the circuit through the socket by way of short-circuiting the terminals of the one associated end of the related tube.

5. A fluorescent gas discharge tube lighting system comprising, a transformer having a primary winding and two secondary windings, two fluorescent lighting tubes individually corresponding to the secondary windings, and sockets into which the terminals of said tubes are positioned connected to said secondary windings, at least one of said sockets being also connected serially with the primary winding and being so constructed as to effect a short-circuit across tube terminals upon insertion of the associated tube to complete the primary circuit and upon removal of the tube open the primary circuit and deenergize the secondary winding corresponding to the other tube.

6. A fluorescent gas discharge tube lighting system comprising, an autotransformer having a primary winding and two secondary windings,

two fluorescent tubes individually corresponding to the secondary windings, and connections including sockets into which the terminals of said tubes fit between the transformer and tubes such that the insertion of a tube short-circuits the socket by way of the tube terminals and completes the primary and secondary circuits and removal of the tube opens the primary circuit and deenergizes the secondary winding corresponding to the other tube.

7. A fluorescent tube illumination system comprising a high leakage reactance autotransformer having groups of parallel magnetic paths and paired primary and secondary coils in each group of magnetic paths, the primary coil being adapted to be connected across a source of alternating electrical energy, and the secondary coils being series-connected across said primary coils and each being adapted to energize a series-connected fluorescent tube, and a cutout relay and high resistance load controlled thereby substantially equivalent to the associated tube load and branched across each secondary coil and having electrical characteristics such that it comes into operation to shunt said secondary coil with said high resistance upon over-voltage attendant upon failure of the tube load energized by the associated secondary coil, whereby balanced operation of said transformer is preserved.

8. A gas discharge tube lighting system comprising, a transformer having a primary winding and two secondary windings, two lighting tubes individually connected in circuits with the secondary windings, and delayed-action high voltage control means electrically connected with the secondary windings and actuating a resistance element substantially equivalent to the tube load so as to shunt said resistance across a secondary winding and prevent over-voltage therein attendant upon tube failure, and whereby balanced operation of said transformer is preserved.

9. A gas discharge tube lighting system comprising, an autotransformer having a primary winding and two secondary windings, two lighting tubes individually connected in circuits with the secondary windings, and delayed-action high voltage controls, each comprising a relay actuating a high resistance shunt circuit substantially equivalent to the tube load and individually connected electrically with the secondary windings so as to shunt a resistance across the associated secondary winding and prevent over-voltage therein attendant upon tube failure, and whereby balanced operation of said transformer is preserved.
